UNITED STATES PATENT OFFICE

ROLANDIS A. BLAIR, OF FORT WAYNE, INDIANA, ASSIGNOR TO THE P & M COMPANY,
OF CHICAGO, ILLINOIS, A CORPORATION OF ILLINOIS.

RAIL ANCHOR.

Application filed January 15, 1926. Serial No. 61,407.

My invention relates to rail anchors and has for its principal object the provision of a one-piece anchor device of improved construction, whereby the device is tensioned during its application to a rail, so as to exert a strong resilient grip, both vertically and transversely of the rail base.

Another object is to provide an anchor having the characteristics above referred to, which can be applied by driving it transversely of the rail base from one side thereof, and which is so constructed that an anchor of one standard size may be applied to rails of different sizes.

Another object is to provide an improved anchor construction which exerts both vertical and transverse spring grips on the base of the rail, which maintains the maximum tension to which it is subjected during its application, and which increases the grip of the device both vertically and transversely of the rail when the device is subjected to creeping pressure.

The invention consists of such further new and improved construction as will be hereinafter described and claimed for carrying out the above stated objects and such other objects as will appear from the following description of the embodiment shown in the accompanying drawing.

In the drawing:

Fig. 1 is a plan view of the base portion of a railroad rail showing a rail anchor device constructed in accordance with my invention applied in its operative position thereon.

Fig. 2 is a side view in elevation showing in dotted line position, one of the positions assumed by the anchor during its application to the base flange of the rail.

Fig. 3 is an end view of the anchor taken at the left of Fig. 2, and

Fig. 4 is a view in perspective of the anchor device illustrated in the preceding figures.

The embodiment of my invention shown in the drawing is made preferably from a steel bar 10, preferably, though not necessarily, round in cross section, bent to the configuration shown in the drawing. As will be seen from an inspection of the drawings, one end of the bar is bent upwardly to provide a shoulder 11 for engaging one of the vertical faces of the base 12 of a

railroad rail. The straight body portion 10 of the bar normally bears against the bottom surface of the rail and is bent downwardly and upwardly to provide a loop 14. The said loop is so positioned with respect to the shoulder portion 11 that the upstanding arm 14 of the loop normally bears against the vertical edge of the rail base at the opposite side of the rail. The upstanding arm 14 is bent to provide an angularly disposed U-shaped jaw 15, the free end 16 of which is bent downwardly to provide a vertical arm 14^a which aligns with the arm 14. The arms 14, 14^a are disposed on opposite sides of the body portion 10, so as to contact with the edge of the rail base at points on opposite sides of the body. This arrangement serves to hold the straight body portion 10 of the anchor in a position substantially at right angles to the longitudinal edges of the rail base so that the engagement of the shoulder 11 with the opposite edge of the rail base will be at a point substantially midway between the said arms 14, 14^a. The jaw portion 15 is so formed with respect to the body portion 10 of the anchor that the vertical distance between the jaw and said body portion, when the anchor is free of the rail, is normally less than the thickness of the rail base at the point engaged by said members when the anchor is in its applied position, whereby it is necessary to force the said jaw and body portion apart when driving the anchor to its applied position.

The distance between the shoulder 11 and the upstanding arms 14, 14^a when the anchor is free of the rail, is normally less than the width of the rail base to which the device is applied, so that it is necessary to tension the loop portion of the anchor when forcing the shoulder 11 over the edge of the rail base.

In applying the anchor to a rail, the jaw portion 15 is hooked over one base flange of the rail in a position adjacent one of the cross ties 17, so that one of the arms 14, 14^a, will bear against the vertical face of the cross tie. The anchor is then driven from the initial position shown in dotted lines in Fig. 2, to the applied position, by striking the loop portion of the anchor with a sledge. The force of the blow against the loop portion drives the body portion trans-

versely of the rail until the shoulder portion 11 clears the edge 18 of the rail base, whereupon the said shoulder snaps into engagement with the vertical face of the base flange. The transverse movement of the body portion 10 of the anchor reduces the diameter of the loop 13 and thereby tensions the anchor so that the upstanding arms 14, 14^a and the shoulder 11 exert a strong spring grip on opposite edges of the rail base. The hammer blows against the loop, in addition to driving the body portion transversely of the rail, force the jaw 15 upon the inclined surface of the rail base. This movement of the jaw tends to further tension the loop portion of the anchor so as to exert a strong spring grip of the jaw and body portion 10 upon the top and bottom surfaces respectively, of the base flange 12 of the rail base. The tendency which the spring loop has to expand to the position from which it was sprung, exerts a strong spring pressure through the jaw 15 and body 10, against the upper and lower surfaces, respectively, of the rail base, and exerts a strong spring grip through the arms 14, 14^a and the shoulder 11 horizontally across the rail base. The spaced arms 14, 14^a hold the body portion 10 and the shoulder 11 in a centralized position with reference to the said arms, and at substantially right angles to the length of the rail.

With the arrangement shown any creeping pressure tending to move the shoulder 11 nearer the tie, will increase the distortion of the loop 13 and thereby increase the grip of the device on the rail. The depending arms 14 and 14^a are so positioned with respect to the body portion of the anchor that the anchor may be applied in its initial position with one of the said arms in engagement with a cross tie, there being sufficient clearance between the cross tie and the upper portion of the loop 13 to permit the anchor to be driven to its applied position without danger of striking the adjacent tie. The relatively large loop 13 provides maximum resiliency whereby the device may be adjusted to the base flange of rails of various widths and thickness, without danger of impairing the resiliency of the anchor.

While I have described my invention in connection with a preferred embodiment, it is obvious that various changes in the construction of the embodiment shown might be made without departure from the spirit of my invention. I therefore contemplate all of the modifications in structure as come within the scope of the appended claims.

I claim:

1. A rail anchor comprising a body member provided with means for engaging the base of a rail at opposite sides of the rail,

and provided with a yielding portion adapted to exert spring pressure both vertically of and horizontally across the rail base.

2. A rail anchor comprising a body member comprising means for engaging the base of a rail at opposite sides of the rail, and formed with a bend which is normally distorted when the anchor is applied to the rail and adapted to exert spring pressure both vertically of and horizontally across the rail base.

3. A rail anchor comprising a body member provided with means for engaging the base of a rail at opposite sides of the rail, and formed with a spring loop adapted to exert spring pressure both vertically and horizontally of the rail base.

4. A rail anchor comprising a body member provided with means for engaging the base of a rail at opposite sides of the rail and formed with a spring loop adapted to bear against the cross tie and to exert spring pressure both vertically and horizontally of the rail base.

5. A rail anchor comprising a body member provided with means for engaging the base of a rail at opposite sides of the rail and formed with a spring loop, the diameter of which is decreased by movement of said rail engaging means to normal operative engagement with the rail base.

6. A rail anchor comprising a body member formed at one side of a rail with a spring loop, which exerts spring pressure both vertically and laterally of the rail, one end of the loop being positioned to engage the adjacent edge of the rail base and the other end of which extends across beneath the rail base and engages the edge of said base at the opposite side of the rail.

7. A rail anchor comprising a body member formed at one side of a rail with a spring loop, one end of which engages the adjacent edge of the rail base and the other end of which extends across beneath the rail base and engages the edge of said base at the opposite side of the rail; the arrangement of the rail engaging portions being such that, in applying the anchor to its operative position on a rail, the said loop is distorted to increase the effective length of the end which extends across beneath the rail base.

8. A rail anchor comprising a body member formed at one side of a rail, with a spring loop, one end of which engages the adjacent edge of the rail base and the other end of which extends across beneath the rail base and engages the edge of said base at the opposite side of the rail; the arrangement of the rail engaging portion and said loop being such that the loop is distorted in applying the anchor to its normal operative position on the rail whereby spring pressure

is exerted both vertically and horizontally of the rail base.

9. A rail anchor comprising a body member formed at one side of a rail with a 5 spring loop which is resilient both vertically and laterally of the rail, one end of which loop engages the vertical edge and the upper surface of the rail base, and the other end of which extends across beneath the rail 10 base and engages the edge of said base at the opposite side of the rail.

10. A rail anchor comprising a body member formed at one side of a rail with a 15 spring loop which is resilient both vertically and laterally of the rail, one end of which loop engages the rail base at one side of the rail and the other end of which extends across beneath the base of the rail and engages the opposite edge thereof.

20. 11. A rail anchor comprising a body formed with a spring loop, one end of which is bent to provide vertically disposed arms at opposite sides of the body, adapted to bear against one edge of the rail base and the other end of which is formed with 25 means adapted to snap over the opposite edge of the rail base.

30. 12. A rail anchor comprising a body formed with a spring loop, one end of which is bent to provide vertically disposed arms at opposite sides of the body, adapted to bear against one edge of the rail base and the other end of which is formed with means adapted to snap over the opposite edge of 35 the rail base; the arrangement of said arms and said means being such that the loop is distorted in applying the anchor to a rail, whereby the rail gripping portions of the anchor are held in position by the resiliency 40 of said loop portion.

45. 13. A rail anchor comprising a body formed with a spring loop which is resilient both vertically and laterally of the rail, one end of which loop is bent to provide a vertically disposed arm and a jaw for engaging one edge and the upper surface respectively, of a rail base, and the other end of which bears against the bottom surface of a rail base adjacent said jaw and formed with 50 means for engaging the opposite edge of the rail base.

55. 14. A rail anchor composed of a bar bent to provide a spring loop, one end of which is bent to form a jaw and spaced vertically disposed arms adapted to engage the rail base at one side of the rail, and the other end of which engages the bottom of said rail base below said jaw, and formed with means adapted to engage the rail base at the 60 opposite side of the rail.

65. 15. A rail anchor composed of a bar bent

to provide a spring loop, one end of which is bent to form a jaw and spaced vertically disposed arms adapted to engage the rail base at one side of the rail, and the other end of which extends between said arms and engages the bottom and the opposite edge of the rail base; the distance between said jaw and the arms engaging the bottom of the base being normally less than the thickness of the base, whereby these members are forced apart in applying the anchor to a rail.

70. 16. A rail anchor composed of a bar bent to provide a spring loop, one end of which is bent to form a jaw and spaced vertically disposed arms adapted to engage the rail base at one side of the rail, and the other end of which extends between said arms and engages the bottom and the opposite edge 75 of the rail base; the distance between said jaw and the arm engaging the bottom of the base being normally less than the thickness of the base, and the arrangement of said vertically disposed arms with relation to the means for engaging the opposite edge of the rail base being such that the said loop is distorted, in application of the device to a rail, to exert spring pressure both vertically and horizontally of the rail base.

80. 17. A rail anchor composed of a bar bent to provide a spring loop, one end of which is bent to form a U-shaped jaw for engaging the top surface of a rail base at one side of the rail, and to form spaced vertically disposed arms adapted to bear against a stationary part of the roadbed, the other end of said loop being arranged between said arms and formed at its extremity with a shoulder 85 for engagement with the rail base at the opposite side of the rail.

90. 18. A rail anchor composed of a bar bent to provide a spring loop, one end of which is bent to form a U-shaped jaw for engaging the top surface of the rail base at one side of the rail and to form spaced vertically disposed arms adapted to engage the adjacent edge of the rail and bear against a stationary part of the roadbed, the other end of said loop being arranged between said arms and formed at its extremity with a shoulder 95 for engagement with the rail base at the opposite side of the rail; the arrangement of said jaw, vertically disposed arms and said shoulder being such that said loop is distorted to exert spring pressure both vertically and horizontally of the rail base and whereby said transverse pressure is increased during the presence of creeping pressure on the rail.

110. 115.
